HERVEY N. ANDREWS AND ROY M. HOLMES, OF SOUTH BEND, INDIANA.

AIR-CONDITIONING APPARATUS FOR DRYING-KILNS.

1,343,894.

Specification of Letters Patent. Patented June 22, 1920.

Application filed May 2, 1918. Serial No. 232,084.

To all whom it may concern:

Be it known that we, HERVEY N. ANDREWS and ROY M. HOLMES, citizens of the United States, residing at South Bend, in the county of St. Joseph and State of Indiana, have invented certain new and useful Improvements in Air-Conditioning Apparatus for Drying-Kilns, of which the following is a specification.

10 This invention relates to an improvement in drying kilns, houses, or rooms, wherein automatic humidity control is provided for the drying agent.

In kiln drying, particularly of lumber, 15 temperature, circulation, and humidity, in proper proportion, are essential to drying, and while temperature and circulation have been heretofore directly and relatively controlled, no direct and relative control of the 20 humidity has been heretofore proposed. Such humidity control devices as have been heretofore used, have been set for a maximum and minimum degree of humidity, and the regulating devices controlled at such 25 maximum and minimum degree points. This permits a variation which is rather detrimental to a proper drying operation, and is in no sense a humidity control.

The present invention contemplates a 30 system which is automatically responsive to any and all sources of humidity entering into the drying operation, and maintains, with a slight variation, a predetermined percentage of relative humidity independently 35 of maximum and minimum limits.

In the system of the present invention, steam jet lines are arranged to coöperate with the usual heating coils to supply moisture to build up the relative humidity, and 40 condensing coils, for the circulation of cold water, are arranged to remove the moisture from the circulating heating medium. Valves are arranged to control the steam-jet feed and the water to the condensing 45 coils. A hygrometer control is arranged to simultaneously and oppositely actuate the valves, to thereby govern the steam jet lines and water flow through the condensing coils, to thus regulate the humidity.

50 The invention will be described in the following specification, reference being had to the accompanying drawings, in which:

Figure 1 is a sectional view, partly in elevation illustrating the improved system.

Fig. 2 is a view in elevation, partly in 55 section of the hygrometer control.

The invention is here shown as embodying a compartment, designed to indicate any kiln, house, or room for drying material. The compartment 1, has the usual floor 2, 60 preferably as spaced stringers, on which are laid rails 3, if such are desired. The usual partitions 4 are arranged adjacent the walls of the compartment, forming down flues for the necessary circulation.

In its specific embodiment, the invention includes condensing coils 5, arranged in the down flues, and in any preferred order, the coils receiving water from a common supply through a pipe 6, and discharging through 70 a common outlet, as a pipe 8. In addition to the usual heating coils 7, which may be of any desired construction, the invention contemplates the use of steam jets 9, arranged below the floor 2, and adapted to 75 jet steam into the surrounding air when it is desired to increase the humidity. The particular arrangement and construction of these steam jets is immaterial for the purposes of the present invention, the intention 80 being that, as with the condensing coils, such jets will be arranged and located with particular regard to the nature of the compartment and material to be dried.

Essentially however, the steam jets should 85 be supplied from a common source, as through a pipe 10. A valve 11, preferably of the Mason balance type, though any suitable valve will serve the purpose, is arranged to control the delivery of the steam 90 to all the jets 9, while an appropriate valve 12 is adapted to control the discharge pipe from all the condensing coils, so that through these valves the steam may be cut off, and the flow of the condensing medium, 95 as cold water, through the coils prevented.

The introduction of the steam from the jets will increase the humidity of the drying agent, while the effective operation of the condensing coils will take the moisture from such agent. If then there is provided a means whereby the valves 11 and 12 may be controlled with accuracy, the percentage of humidity of the drying agent may be regulated.

The control means is here shown as a hygrometer, so that the degree of humidity of the drying agent is the control element.

Therefore, the relative percentage of humidity in the drying agent is directly controlled by the humidity present. The hygrometer, as seen in Fig. 2, comprises a case 13, open to the drying agent, in which, on a post 14 is mounted a combined indicator and switch arm 15, the movement of the arm being balanced by a weight 16. The free end of the arm plays over a segment strip 17, marked, as in degrees, and said arm has secured thereto, slightly beyond the pivot, one end of a hygrostatic element 18, as human hair, the other end of which is secured to a post 19, secured in the case. The element 18, responding to the moisture content of the heating agent, will compel a corresponding movement of the free end of the arm, and this movement is utilized as a means for operating the valves 11 and 12, hereinbefore referred to.

The valve operating means comprises a solenoid, or similar device, as 20, the core 22 of which is connected to an operating rod 21. One end of the rod 21 is connected to the stem of what may be termed the water valve 12, being pivotally mounted at 23, adjacent said stem, while the other end of the rod 21 is connected by a link 24 to the operating arm 25 of the steam valve 11. A weight 26, tends to maintain the steam valve closed under normal conditions.

The valves 11 and 12 are located adjacent to each other and in opposite directions beyond the solenoid, so that by the arrangement described, the action of the solenoid will actuate both valves simultaneously, but oppositely, that is when opening one it will close the other.

The hygrometer previously described is designed to control the solenoid, and while any desired means may accomplish this result, it is preferred to provide a relay 27, which governs the solenoid circuit, here shown as ordinary lighting service mains 28. The action of the relay is governed through a local circuit, including conductors 29 and 30, having a battery in circuit, as at 31.

The terminals of the local circuit lead to the hygrometer, one terminal connected to the post pivotally supporting the switch arm 15, so that the arm is in circuit. The other terminal of the local circuit leads to the indicator strip 17, so that this strip is in circuit. A slide 32 is adjustable on the strip 17, and is formed so that it may be positioned on the strip above or below the free end of the arm 15, or two such strips may be employed, if desired.

As the free end of the arm 15 does not contact with the strip 17, it is apparent that the local circuit is normally open, but that when the end of the arm contacts with the slide, such local circuit is closed, the relay operated, and the solenoid energized to op-

erate the valves 11 and 12. If therefore, the slide 32 is set at any particular point, the moisture content below such point, the other parts being adjusted accordingly, will operate the valves 11 and 12.

To set the structure to maintain a constant relative humidity, say fifty per cent., the slide 32 is set at the 50° on the scale strip. If the humidity is lower the arm 15 closes the local circuit, the valve 11 is opened and the valve 12 is closed. The condensation stops and the steam jets add to the humidity of the air until the local circuit is broken, when the parts are gradually restored. If the humidity should be above the percentage required, the valve 11 is maintained closed and the condensing coils function to reduce the humidity.

As the relative humidity varies above or below the desired percentage, the valves 11 and 12 are controlled accordingly. The device is placed directly within the drying compartment, and the moisture derived in the initial heating of lumber for example, will directly affect the hygrostatic element, so that this source of humidity is taken into account and provided for in the present invention.

Any desired type of hygrometer capable of the function noted may be used, and, of course, any type of valves are contemplated. The use of the invention as a system is readily applicable to any and all drying systems where it is desired to directly and automatically control the relative humidity of the drying agent.

It is to be noted that when the steam jets are in operation, as by opening the valve 11, the escape of the water from the condensing coils is cut off, as the valve 12 is closed. Under these circumstances, the water in the coils will rapidly heat up under the heating agent to a non-condensing heat, so that the moisture-reducing function of the coils is interrupted, without, however, any waste of water. If the system did not provide for such action, there would be required an additional degree of heat to overcome the condensing function of the coils. Therefore the invention tends to an economical use of heat and water, at least to the extent noted.

Having thus described the invention, what is claimed as new, is:—

1. In a drying kiln, means for adding to the humidity of the air, means for taking moisture from the air, and synchronized means including a control element governed by the degree of humidity in the air for controlling both of said means.

2. In a drying kiln, means for adding moisture to the air, means for taking moisture from the air, and synchronized means including a control element governed by the degree of humidity in the air for simul-130

taneously controlling and reversely influencing both such means.

3. A drying kiln including a steam jet and a water supplied condenser, valves operatively connected for controlling the steam and water supply to the jet and condenser in relatively reverse order, whereby one of the mediums will be cut off during the flow of the other, and means governed by the
- 10 moisture in the air for controlling the operation of the valves.

4. A drying kiln including a steam jet

and a water supplied condenser, valves operatively connected for controlling the steam and water supply to the jet and condenser 15 in relatively reverse order, whereby one of the mediums will be cut off during the flow of the other, and a hygrometer for controlling the operation of the valves.

In testimony whereof we affix our signatures.

HERVEY N. ANDREWS.
ROY M. HOLMES.
